UNITED STATES PATENT OFFICE.

DELOS CARPENTER, OF ORION, MICHIGAN.

FOLDING UMBRELLA.

SPECIFICATION forming part of Letters Patent No. 646,725, dated April 3, 1900.

Application filed November 29, 1897. Serial No. 660,051. (No model.)

To all whom it may concern:

Be it known that I, DELOS CARPENTER, a citizen of the United States, residing at Orion, county of Oakland, State of Michigan, have 5 invented a certain new and useful Improvement in Folding Umbrellas; and I declare the following to be a full, clear, and exact description of the invention, such as will enable others skilled in the art to which it appertains to make and use the same, reference being had to the accompanying drawings, which form a part of this specification.

My invention has for its object certain new and useful improvements in umbrellas; and 15 it consists more particularly of a folding umbrella of novel construction and utility.

My invention consists of the construction, combination, and arrangement of devices hereinafter described and claimed, and illustrated in the accompanying drawings, in which—

Figure 1 is a view of an umbrella-frame, showing parts in vertical section and parts in elevation. Fig. 2 is an enlarged view, 25 partly in section and partly in side elevation, of the notch and related parts. Fig. 3 is an enlarged detail view of portions of the umbrella-handle and ferrules with the notch attached, the same being that portion above the 30 horizontal dotted line 33 in Fig. 1. Fig. 4 is an enlarged view of portions of the ferrules D and E with the inner rods and their connections. Fig. 5 is a detail view showing a bayonet-joint of the upper umbrella-rod with 35 the adjacent ferrule. Fig. 6 is a side elevation of the features of the device illustrated in Fig. 2. Fig. 7 is a detail view of the handle or stick of the umbrella shown in elevation and partly in section, showing the ferrules in place to hold the handle in rigid position. Fig. 8 is a side elevation showing the 40 ferrules moved into position to permit the folding of the inner portions of the handle, and Fig. 9 shows the handle in partially-folded 45 position.

The aim of my invention is to provide a folding umbrella which may readily be folded up into compact form and which may conveniently and quickly be folded and erected 50 in the form of the usual umbrella for use, the umbrella when in position for use being firm at every part and of tasty appearance.

The drawings show the umbrella-cover omitted.

I carry out my invention as follows: 55

A, B, and C represent three portions constituting my umbrella-handle proper, said parts A, B, and C made of customary tubing or otherwise and jointedly connected at their adjacent ends, as by links, (indicated at a and b.) These links may be riveted or otherwise secured with the adjacent parts of the handle. By means of this construction the three rods of the handle may readily be folded when the joints are free to move. Upon the parts A 65 and B of the handle are sleeved long ferrules, (indicated at D and E.) Beneath the ferrule E is an additional ferrule F, stationary upon the lower end of the handle. The ferrules D and E are constructed and arranged to normally sleeve over the joints a and b in the handle-rods when the umbrella is in position for use, so as to hold said joints rigid. In this position the ferrules D and E are held in connected position in any suitable manner, 70 as, for example, by a suitable spring-latch, (indicated at e, Figs. 1 and 4,) one end of the latch being secured firmly within one of the ferrules, the opposite (as the upper) end of the latch catching or hooking into the adjacent 75 end of the corresponding ferrule, the corresponding ferrule being provided with any suitable notch or opening, as at e', for that purpose. G denotes the ribs, which are formed of two parts G' and G². These ribs may be 80 jointedly connected at their adjacent ends in any suitable manner, as at g, as in the manner, for example, described and shown in a patent granted to me by the United States Patent Office for a folding umbrella, No. 577,234, 85 dated February 16, 1897, the joint being such that the lower portions G' may be folded upward and outward over and alongside the upper portions G², the upper ends of the portions G² being connected with a top notch H, 90 as hereinafter described. My present invention is not limited to any particular method of constructing the joint connecting the portions G' and G².

J denotes the brace-rods, united at their inner extremities to a runner K in a customary manner and at their outer ends with the upper portions G² of the ribs, as at j, in any suitable manner. The runner K is sleeved 100

upon the ferrule D. A spring-catch L is provided in a customary manner to support the runner. The jointed connection of the brace-
5 rods with the runner is indicated at j'.
A very important feature of my present in-
vention consists in the construction of the
head or top notch H and the manner of its
connection with other parts of the umbrella-
frame, one of my chief objects being to pro-
10 vide a top notch which shall be of small di-
mensions, and thereby give a tasteful appear-
ance to the umbrella, and yet to provide am-
ple facility for the working of the parts in
connection therewith. Instead of employing
15 a chambered top notch, as embodied in my
patent above referred to, wherein the upper
end of the runner may be received in the
operation of the device to permit the braces
being thrown sufficiently upward to permit
20 the folding and unfolding of the ribs and to
permit the braces J being folded upward and
inward alongside the folded ribs, I now con-
template a top notch connected, in the in-
stance shown in the accompanying drawings,
25 with the upper ferrule D at the upper end of
said ferrule, the notch being secured over the
upper end of the said ferrule in any suitable
manner, as indicated at h. It will be obvi-
ous that in order to fold the ribs and braces
30 upward the runner must be slipped upward
upon the sleeve D past the center or past a
horizontal line drawn through the two joints
j, and in order to accomplish this end some
expansion must be afforded to the ribs in their
35 connection with the top notch. In dotted
lines in Fig. 1 I show the position assumed
by the runner when slipped up against the
upper notch into folded position. My present
invention therefore contemplates an expan-
40 sible top notch, the same being constructed, as
shown, of a hollow or tubular body H', se-
cured upon the ferrule D, the notch being
constructed with peripheral recesses, (indicated
at h'), said recesses opening downward
45 and also opening outward to receive expand-
able intervening devices or links H², jointed-
ly connected at their upper ends with said
recesses, as indicated at h², forming a part of
the notch and making the notch expansible,
50 said links being jointedly connected at their
opposite ends, as indicated at h³, to the cor-
responding ribs G. When the runner K is
forced upward in passing the center above
mentioned, the links H² will open outward,
55 thus permitting the runner to pass the cen-
ter; but when the runner is forced up into
contact with the notch H the links H² will
fold inward and about the upper end of the
runner, as indicated in dotted lines in Fig. 1.
60 To prevent an undue expansion of the head
or of the connection of the ribs therewith,
the top notch is preferably provided with a
cap H³, projecting over the body H' of the
notch and into proximity with the upper edges
65 of said recesses to form a stop for the upward
movement of said links H². The body H' of
the notch and its cap H³ may be held in place

upon the ferrule D in any suitable manner;
as by a nut H⁴. The notch thus constructed
and embodying the links H², united there-
with, forms an expansible notch and may be
of small dimensions. The notch is prefer-
ably constructed with two links H² to engage
each of the portions G² of the ribs.

The upper end of the portion A of the han-
dle-rods, it will be perceived, passes through
the notch and through the upper end of the
ferrule D and projects thereabove when the
umbrella is in expanded position. The lower
end of the portion C of the handle-rod pro-
jects through the lower end of the ferrule E
and is provided with a knob or other suitable
hand grasp. To fold up the umbrella, the
spring stop or latch at e is released from the
upper ferrule D, and the handle is then pulled
downward, so as to bring the handle-joint a
downward in juxtaposition to the joint of the
two ferrules D and E, permitting the handle-
rods to be folded at that point, as at the dotted
line 3 3, Fig. 1. The handle is also moved
into position where the joint b is in juxtapo-
sition with the joint of the ferrules E and F,
as at the dotted line indicated at 4 4, Fig. 2,
permitting the joint of the umbrella-rods to
be flexed or bent. The manner of folding up
the ribs and braces has already been de-
scribed. The manner of unfolding and erect-
ing the umbrella for use or of putting it into
the condition of an ordinary umbrella will
readily be understood. The runner is run
down upon the adjacent sleeve to the required
position, the lower portions of the ribs are
folded downward into place, and the jointed
portions of the handle-rods are held in rigid
position by suitable movements of the ferrules
D and E. Should the spring-stop at e be not
sufficient to hold the adjacent parts rigid and
firmly as against a shock or jar upon the up-
wardly-projecting end of the umbrella-han-
dle, my invention contemplates constructing
the ferrule D with a laterally-projecting ori-
fice (indicated at d, Fig. 5) communicating
with the vertical elongated slot d' in said fer-
rule, permitting the umbrella-handle to be
partially turned about to engage the upper end
of the spring-stop in the laterally-projecting
orifice. This bayonet-joint will firmly hold
the parts under all circumstances. I do not
limit myself, however, solely to this construc-
tion, as the handle may be held firmly in po-
sition for use in any suitable manner. The
employment of the long ferrules D and E with
their spring-stop enables me to hold the han-
dle and ferrule in rigid position when set for
use.

I prefer that the links connecting the ribs
with the body of the top notch should be of
curved form, so as to close more compactly
inward about the upper end of the runner.

While I have shown and described in con-
nection with the accompanying drawings my
improved expansible top notch connected
with the upper end of a ferrule upon the han-
dle-rods, I would have it definitely under-

stood that I do not limit the application of my expandible top notch to the ferrule alone, inasmuch as the top notch may be used equally well upon handles of other constructions, as upon handles, for example, like that embodied in my patent above referred to, or still other modifications in the constructions of umbrella-handles, and my invention is therefore designed for use upon any form or 5 construction of umbrella-handles wherever it may be found applicable and wherever it is desired to have the top notch expand to receive a runner and to close down compactly when the umbrella is in position for use, so as to 10 present a neat and tasty appearance, such an appearance requiring a small top notch. It will be perceived that the expandible notch contracts or closes inward at all times except when it is desired to expand the same 15 in order to permit the runner to pass the center and allow the umbrella to fold neatly. I do not limit myself to any particular number of expandible portions connected to the body of the notch, nor to any particular shape or 20 form of the same, nor to any specific manner of fastening it in place. The expandible top notch is applicable within the scope of my invention to any folding or telescoping umbrella. This head or top notch, with its cap, 25 may be made in the form of a very neat small tapering device, thereby getting around the objectionable feature of a large head or notch heretofore common in various constructions 30 of umbrellas. Moreover, I would have it definitely understood that I do not limit myself to the construction of my improved head 35 or top notch with the cap as a part thereof, as the cap might be omitted without departing from the scope of my invention, inasmuch 40 as when the cover is on tight or the parts are firmly connected and in place in the complete umbrella, the actions of the expandible features will govern themselves without requiring at all times the presence of the cap. 45 It will be perceived that the three portions

or handle- rods A B C of the handle are sleeved through the ferrules D and E, said ferrules simply being held in engagement with said rods by the spring-latch e, said ferrules thereby stiffening said handle- rods. By 50 depressing the spring-latch e the handle- rods A B C may be entirely slipped out of said ferrules. In this way the handle- rods are separable and detachable entirely from the ferrules, while the lower handle- rod C also forms 55 or is made a part of the knob or other similar device. This construction greatly facilitates the construction of the handle as a whole and simplifies and cheapens any repair of these parts of the umbrella. 60

What I claim as my invention is—

1. In a folding umbrella, the combination of the top notch, the ribs, the runner, and the braces connecting the runner with the ribs, said runner arranged to slip upward against 65 the notch, and the notch provided with expandible devices connecting the ribs therewith to permit said movement of the runner, and the notch closing inward about the upper end of the runner when in a folded position, substantially as set forth. 70
2. In a folding umbrella, the ribs constructed of two jointedly-connected rigid sections permitting the lower sections to fold outward and upward, a top notch provided with expandible devices having a jointed connection with the upper ends of the upper sections of the ribs, permitting the upper sections to also fold upward, a runner, braces jointedly connecting the runner with the upper sections of 75 the ribs, said runner arranged to slide upward past the center to permit the upward folding of the upper sections of the ribs, substantially as set forth. 80

In testimony whereof I sign this specification in the presence of two witnesses.

DELOS CARPENTER.
